JACKSON C. FRICKE, OF BROOKLYN, NEW YORK, ASSIGNOR TO INTERNATIONAL COMMUNICATIONS LABORATORIES, INC., OF NEW YORK, N. Y., A CORPORATION OF NEW YORK

PRINTING TELEGRAPH MOTOR CONTROL

Application filed June 25, 1931. Serial No. 546,715.

This invention relates generally to printing telegraph exchange systems, and more particularly to such systems in which the subscribers' lines are normally open to direct current and are closed when alternating current is applied to these lines at the central station.

One of the principal objects of this invention is to increase the operating range of the printers at the interconnected central and subscriber's stations by removing the alternating current relay, used to close the subscriber's line to direct current, from the line while communication is being carried on.

Another object is to provide means for indicating to the central station operator that the subscriber's station printer motor has been started.

The present invention is an improvement upon an invention disclosed in a previous application, Serial No. 469,393, filed July 21, 1930 in the name of applicant. According to the invention disclosed in that application, an alternating current relay at the subscriber's station is operated by alternating current applied to the subscriber's line at the central station. The operation of this relay closes the line to direct current, and a mechanical locking device actuated by the relay then maintains the line closed while communication is carried on.

It has been found that the alternating current relay, which remains connected to the line circuit during signal transmission, has a tendency to reduce the operating range of the connected printers, and that retractive signalling means are necessary to inform the central station operator that the subscriber's station printer motor has started. In the absence of the last-mentioned means, the central station operator might frequently send messages to an unattended subscriber's station printer that could not be started, due to some local circuit trouble, without any knowledge that such messages had not been received.

Accordingly, one feature of this invention is the extension of the circuit for operating the alternating current relay, through a con-

tact of a motor control relay, whereby the former relay is removed from the subscriber's line circuit as soon as the latter operates.

Another feature is the provision of a relay that is operated, when the subscriber's printer motor has reached a certain speed, to close a shunt around the motor control relay, thus increasing the line current to cause the lighting of a supervisory lamp at the central station operator's set to indicate that the subscriber's station motor has started.

Referring now to the drawing, O designates the central station operator's set, C the central station concentration board, and S the subscriber's station. Only the elements necessary to a clear understanding of the invention have been shown, but it is obvious that by adding similar elements to those illustrated it would be possible to construct a printing telegraph exchange system capable of handling any desired number of subscribers.

The subscriber's station S is connected with the central station concentration board C by a line 1 that is closed to alternating current through a winding of alternating current relay 5 but is open to direct current by reason of the condenser 2 and the normally open contact A of switch 6. When the alternating current relay 5 is operated, the switch 6 is operated to close its contacts and thus close the line circuit 1 to direct current. In this closed line circuit is a slow-releasing motor control relay 4 whose functions are to control the operation of the slow-operating restoring relay 3, to start and stop the printer motor 12, and to disconnect the alternating current relay 5 from the line circuit 1 while communication is being carried on. The restoring relay 3, which is operated only when the line circuit 1 is broken at the concentration board C, is adapted to restore the switch 6 to its normal position and thus reopen the subscriber's line circuit 1 to direct current. Associated with the printer motor 12 is a relay 13 which is operable, after the printer motor has reached a certain speed, to form a shunt for the line circuit 1 through a resistance 7 and around the high resistance of the

motor control relay 4 and thus cause the lighting of a supervisory lamp at the central station, in a manner to be described hereinafter, to indicate that the printer motor 12 has started. To permit the subscriber's station S to call the concentration board C, a calling key 14 is provided and this key, when operated, closes the line 1 to direct current to light a supervisory lamp at the board, as 10 will be described in detail below.

At the concentration board C are disclosed jacks 15 and 16 which are individually associated by line 1 with the subscriber's station S. Connected through the contacts of these 15 jacks and variable resistance 20 to subscriber's line 1 is a line relay 17 having both an operating and a locking winding. The circuits for energizing these windings are controlled by slow-releasing relay 18 which is 20 connected to grounded negative battery 19 and to the sleeve of jack 16. This relay releases more slowly than motor control relay 4 at the subscriber's station S in order to permit restoring relay 3 to operate and open 25 the line 1 to direct current before the release of relay 18 connects battery to the line 1. Controlled by the line relay 17 is a supervisory lamp 21 individual to the subscriber's station S.

Co-operating with the jacks 15 and 16 is a cord circuit with a tip circuit 22 and a sleeve circuit 23 extending from the central operator's set at O and terminating in a plug at the concentration board C. At the operator's set are alternator 26 and grounded positive battery 27 which are connected to the tip 22 of the cord circuit by the operation of relay 25 and are disconnected by the operation of ring down relay 24. This latter relay also serves to connect the operator's printer to the tip of the cord circuit, to complete a circuit for operating supervisory lamp 32 and to prepare a locking circuit for relay 34. The operator's printer is of the usual type and consists of line relay 29, transmitter 30 and printer magnets 36 associated with a contact of the line relay. This line relay has a continuously energized biasing winding A and an operating winding B whose battery connection is controlled by relay 25. The printer has associated therewith a printer motor which is controlled manually by the key 33 and relay 34. At the operator's printer set is a supervisory lamp 37, and in the same circuit is another supervisory lamp 38 at the concentration board. These lamps are controlled jointly by relay 25 and key 40 which, in turn, controls relay 39.

The operation of the above-described structure, when a call is being extended from a subscriber's station S to a central station printer operator O, will now be described. The subscriber operates key 14 which closes a circuit to operate and lock line relay 17.

The operating circuit may be traced from grounded negative battery 19, contact A of relay 18, winding of relay 17, tip contact of line jack 16, tip contact of supervisory jack 15, variable resistance 20, subscriber's line 1, key 14, winding of restoring relay 3 to ground. The locking circuit may be traced from battery 19, contact B of relay 18, winding of relay 17, contact A of relay 17 to ground. The operation of line relay 17 closes a circuit for lighting supervisory lamp 21, which may be traced from grounded negative battery, lamp 21, contact B of line relay 17 to ground. Upon seeing the lighted lamp, the concentration board operator inserts a plug, with which is associated an unlighted lamp as 38, into the jack 16. This energizes relays 18 and 25 over the sleeve circuit 23, thus releasing line relay 17 and extinguishing supervisory lamp 21. The operating circuit of these relays may be traced from grounded negative battery 19, winding of relay 18, sleeve of jack 16, sleeve circuit 23, winding of relay 25 to ground. The operation of relay 25 closes the circuit 90 of the supervisory lamps 37 and 38, thus informing the printer operator of an incoming call and making the cord circuit busy at the concentration board. The circuit for operating these lamps may be traced from grounded positive battery 28, contact C of relay 25, lamp 38, lamp 37, contact A of relay 39 and ground. The operation of relay 25 also connects grounded positive battery 28 in series with the line relay 29 and the transmitting contacts 30 through contact D of relay 25. At its B contact relay 25 applies alternating current, superimposed on direct current, to the subscriber's line circuit 1 over a circuit extending from grounded positive battery 27, alternator 26, contact B of relay 25, winding and contact A of relay 24, tip 22 of the cord circuit, tip of jack 16, tip of jack 15, variable resistance 20, subscriber's line 1, condenser 2, contact A of restoring relay 3, contact C of motor control relay 4, winding of alternating current relay 5 to ground. The alternating current relay 5 operates over the circuit just traced and closes contacts A and B of the switch 6, thus shunting the condenser 2 and closing the line circuit 1 through contact A of switch 6. The subscriber's line 1 is thus closed to direct current over a circuit from grounded positive battery 27, alternator 26, contact B of relay 25, winding and contact A of relay 24, tip 22, tip of jack 16, tip of jack 15, variable resistance 20, line 1, contact A of switch 6, winding of motor control relay 4, printer magnets 8, transmitter 9 to ground. Upon closure of this circuit, motor control relay 4, but not relay 24, operates, closing at its B contact an alternative circuit to ground which shunts the high resistance of the printer magnets 8, thus accelerating the 125 130

operation of motor control relay 4. The operation of motor control relay 4 being thus accelerated, its A contact is opened in time to prevent the operation of restoring relay 3 over an obvious circuit which was closed by the operation of alternating current relay 5. At its C contact the motor control relay 4 opens the circuit for operating the alternating current relay 5, thus disconnecting this relay from the line circuit 1. The release of alternating current relay 5, however, does not open the contacts of switch 6, but these contacts remain closed until positively opened by the subsequent operation 15 of restoring relay 3. At its D contact motor control relay 4 closes an obvious circuit for operating the printer motor 12 and also a circuit for preparing relay 13 for operation. This latter relay, however, does not operate until the printer motor 12 has 20 reached a certain speed and when this occurs relay 13 operates to shunt the line circuit 1 around the high resistance of the motor control relay 4, thus increasing the current 25 in the line circuit 1. Upon this increase in the line current, relay 24 operates over the circuit previously traced and locks through ground on the A contact of relay 25. Relay 24 opens its A and closes its B contact, thus 30 cutting off the alternating current superimposed on direct current from line circuit 1 and closing this line circuit through the transmitting contacts 30 and windings of line relay 29 to grounded positive battery 35. The operation of relay 24 also closes an 35 obvious circuit for lighting a supervisory lamp 32. Upon seeing this supervisory lamp lighted, the central station operator is aware that the subscriber's printer motor is running 40 at the speed required for reception of signals and he, thereupon, operates key 33 to complete an obvious circuit for energizing relay 34. The energization of this relay completes a circuit for central station printer motor 35. The central station operator 45 and the subscriber's station S are now interconnected. The alternating current relay 5 is removed from the line circuit and communication can now be carried on between 50 the two stations.

When communication has ended, the central station printer operator operates key 40 to energize relay 39 over an obvious circuit. The operation of this relay extinguishes 55 lamps 37 and 38. Upon perceiving extinguished lamp 38, the concentration board operator pulls down the plug from the jack 16, thus breaking the circuit through the printer motor control relay 4 and the relay 18, and 60 de-energizing sleeve relay 25. As the relay 18 releases more slowly than motor control relay 4, it is obvious that the circuit from grounded battery 19 will not be closed through the line relay 17 and through printer motor control relay 4 until after the latter

relay has released. The release of this relay closes a circuit for operating restoring relay 3. This circuit may be traced from grounded positive battery 10, resistance 11, contact A of motor control relay 4, contact B of switch 6, 70 winding of restoring relay 3 to ground. Relay 3 operates, re-opening contacts A and B and thus re-opening the line circuit 1 to direct current at contact A and breaking at contact B the operating circuit of restoring relay 3. As the release of motor control relay 4 opened the circuit for operating the printer motor 12 and relay 3, the subscriber's station is now restored to normal. At the central station operator's set O the removal of the 75 plug from the line jack 16 releases relay 25 which removes grounded battery 28 from line relay 29 and transmitter contacts 30 and breaks the locking circuit for relay 24. Relay 24 releases, reconnecting the winding of this relay to the tip of the plug circuit extinguishing lamp 32, and releasing relay 34 to stop the printer motor 35. All circuits at both the central and subscriber's stations are 80 restored to normal. 85

It is obvious from the above description that the operations when a call is initiated at the central station are similar, and their description is therefore believed unnecessary. 90

What is claimed is:

1. In a printing telegraph exchange system, a first station, a second station, a line normally open to direct current connecting said stations, an alternating current relay connected in said line at said second station and responsive to alternating current applied to said line at said first station for closing said line to direct current, and means responsive to said closure for removing said alternating current relay from said line. 100

2. In a printing telegraph exchange system, a first station, a second station, a printer at said second station and a motor for driving said printer, a line normally open to direct current connecting said stations, means for closing said line to direct current, means responsive to said closure for starting said motor, and means operable when said motor has reached operating speed for causing an indication at the first station that said motor is running. 110

3. In a printing telegraph exchange system, a first station, a second station, a lamp at said first station, a printer, a motor for driving said printer and a relay associated with said motor at said second station, a line normally open to direct current connecting said stations, means for closing said line to direct current, means responsive to said closure for starting said motor, means operable when said motor has reached operating speed for operating the relay associated therewith to increase the current in said line, and means at said first station responsive thereto for lighting said supervisory lamp. 115 120 125 130

4. In a printing telegraph exchange system, a second station, a line normally open to direct current connecting said stations, an alternating current relay connected in said line at said second station and responsive to alternating current applied to said line at said first station for closing said line to direct current, means responsive to said closure for removing said alternating current relay from said line and for conditioning said second station for communication with said first station, and means under control of said first station for reconnecting said relay to said line.
5. In witness whereof, I hereunto subscribe my name this 23rd day of June, 1931.
JACKSON C. FRICKE.
